UNITED STATES PATENT OFFICE.

CHARLES BLESCH, OF NEWPORT, KENTUCKY, ASSIGNOR TO THE CRANE & BREED MANUFACTURING COMPANY, OF CINCINNATI, OHIO, A CORPORATION OF OHIO.

DESIGN FOR A BURIAL-CASKET HANDLE.

Application filed February 24, 1926. Serial No. 16,652. Term of patent 7 years.

To all whom it may concern:

Be it known that I, CHARLES BLESCH, a citizen of the United States, residing at Newport, in the county of Campbell and State of Kentucky, have invented a new, original, and ornamental Design for Burial-Casket Handles, of which the following is a specification, reference being had to the accompanying drawing, forming part thereof, in which the figure is a front elevation of a

burial casket handle, partly broken away, showing my new, original and ornamental design. The end of the handle bar which is broken away is a duplicate of its opposite end.

I claim:

The ornamental design for a burial casket handle, substantially as shown and described.

CHARLES BLESCH.
